(57) **CLAIM**

The ornamental design for a lid with pylons, as shown and described.

DESCRIPTION

FIG. 1 is a top perspective view of a lid with pylons;

FIG. 2 is a bottom perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a rear elevational view thereof; and,

FIG. 8 is a front elevational view thereof.

The ornamental design which is claimed is shown in solid lines in the drawings. The portion depicted in broken lines forms no part of the claimed design.
